Filed Aug. 1, 1962, Ser. No. 213,937
8 Claims. (Cl. 250—213)

This invention relates to crossed-grid electroluminescent phosphor illumination control elements of a type which lends itself to the fabrication of closely packed arrays wherein an array of N^2 on-off control elements may be controlled by $2N$ input functions. More particularly, however, this invention relates to control elements which are designed to radiate predetermined colors in response to predetermined input functions.

Closely packed panel-like arrays of these control elements will provide displays of pictorial data under the control of electronic computer generated data, or, in response to signal information being derived from commercial or closed-circuit TV programs.

Developments of display panels around the use of an electroluminescent phosphor have resulted in a variety of means for subjecting selected areas of a layer of phosphor to the excitation forces of an electric field. But the simplest of these will be found in the crossed-grid types. These consist of a layer of electroluminescent phosphor embedded in a suitable dielectric, sandwiched between a series of parallel conductors on one side and a 90° displaced series of parallel conductors on the opposing side. Such an arrangement of X-Y conductors lends itself to applying a voltage to a single pair of X-Y conductors, subjecting the phosphor to an electric field in an area which coincides with the crossover point of the two conductors. Due to the effects of capacitive coupling between adjacent parallel conductors the electric field will be extended beyond the cross-over point of the two energized conductors. Under such conditions a much larger area of the phosphor will be excited which, of course, results in very poor picture resolution and also brightness, due to the undesirable spreading of light about the area immediately adjacent the crossover point of the initial pair of conductors.

This difficulty with the crossed-grid type of display panel have led to the development of other types of display panels which involve the use of an array of individual phosphor area control elements. The elements used in these developments are well known in the art as nonlinear ferroelectric capacitors, transfluxors, and other similar devices. Although panels using such elements have been shown to have very good light output and contrast ratio, they are extremely complex when compared with the relatively simple crossed-grid display panel. Since resolution appears to be a major problem, the use of ferroelectric capacitors, transfluxors, and the like, seem to be limited to large screen displays.

An important object of the present invention is to improve on the relatively simple crossed-grid display panel approach by overcoming the capacitive coupling difficulties responsible for poor picture resolution and picture brightness.

It is therefore an object of this invention to incorporate the use of light conductor means in combination with photoconductive materials to provide an array of individual phosphor area control elements which lend themselves to the fabrication of either small or large screen displays.

2

A further object is to provide a crossed-grid electroluminescent phosphor illumination control element which is designed to provide light radiation of a predetermined color.

5 Other objects and advantages of the invention will become apparent from the following description when taken in conjunction with the accompanying drawing wherein an individual control element is shown which embodies the basic concepts of the invention.

Referring now to the invention as illustrated, it is comprised of a plurality of first electrodes 2, 3 and 4, a plurality of layers of electroluminescent phosphor 5, 6 and 7, a second electrode 8, photoconductive material 9, and light conductor means 10 for conducting light to the photoconductive material 9. A source of electrical power 11 is provided. One terminal 12 is connected to the second electrode 8 through an on-off switch 13. An opposite terminal 14 is connected to the first electrodes 2, 3 and 4 through separate variable resistors 15, 16 and 17.

15 The first electrodes 2, 3 and 4 are longitudinally extending electrical conductors and preferably optically transparent. An example of a well known material that may be used for this purpose is a conductive material produced by Pittsburgh Plate Glass Co., under the trademark 20 "NESPA" transparent conductive material.

25 The electroluminescent phosphor 5, 6 and 7 is illustrated as being comprised of three longitudinally extending layers each having different color emission characteristics. For example, the layers 5, 6 and 7 may be made to emit, respectively, red, blue and green. However, the layers 5, 6 and 7 may all be made to emit the same color, or, merely white light. In either event the electroluminescent phosphor is embedded in a suitable dielectric and intimately joined with the first electrodes 2, 3 and 4.

30 The photoconductive material 9 may be selected from among certain materials such as selenium, cadmium sulphide, silver selenide, germanium, and like materials, each of which have properties which in total darkness cause the material to be an excellent resistor to electric current, 35 while in the presence of light the material becomes conductive.

35 The light conductor means 10 may be made from such materials as quartz, glass, Lucite, nylon or other similar materials. The light conductor means 10 is longitudinally extending and displaced approximately 90° , or less, with respect to the longitudinally extending electrodes 2, 40 3 and 4, and is spaced apart therefrom. It is preferably a light conducting fiber having a predetermined index of refraction and a light conducting jacket 20 having an index of refraction less than said predetermined index. 45 The jacket 20 is adapted to control the reflection of light through the fiber 10 and the reflection of light to the photoconductive material 9.

50 The second electrode 8 is a longitudinally extending electrical conductor spaced apart from the phosphor layers 5, 6 and 7, and is parallel therewith. The photoconductive material 9 in the spaced apart dimension is connected operatively with the second electrode 8 and the phosphor layers 5, 6 and 7, and intimately joined 55 with the light conductor means 10. The spaced apart dimension 19 between the first electrodes 2, 3 and 4, and the second electrode 8 is sufficiently great enough to avoid any excitation of the phosphor layers 5, 6 and 7 while the photoconductive material 9 is in a state of darkness 60 and while the influence of electrical potentials are across 65

the phosphor 5, 6 and 7 and the photoconductive material 9.

When placed in operation the control unit as illustrated will be subjected to potentials from the source of electrical power 11, and a source of light entering the light conductor means 10 in the direction of arrow 21. Under these conditions light radiation from the phosphor layers 5, 6 and 7 will be viewed from the direction of arrow 22. If, for example, the layers 5, 6 and 7 are designed to emit red, blue and green light respectively, a wide range of color combinations may be viewed from the direction of arrow 22 in response to a similarly wide range of adjustments made to the variable resistors 15, 16 and 17, and upon the closing of the on-off switch 13, and the admission of light to the light conductor means 10.

Although the photoconductive material 9 presents a high degree of resistance to the flow of electrical current when in a state of darkness and a relatively low amount of resistance when exposed to light, the voltage drop across the material 9 between the phosphor and the electrode 8 may be regulated as a function of light intensity entering the light conductor means 10. The intensity of light radiation from the phosphor layers 5, 6 and 7 may, therefore, be under the control of light entering the conductor means 10, while the color of said light radiation is being controlled as a function of the adjustments made to the variable resistors 15, 16 and 17.

Although the invention as illustrated includes the use of but a single light conducting fiber 10, it should, of course, be understood that two or more such fibers of smaller cross sectional dimensional may be utilized within the same space being occupied by the fiber 10. It is well known in the arts that such light conductor means 10 may be made of fibers equal to 0.001" in diameter, or less. Light conducting fibers designed to control the illumination of photoconductive material intimately joined therewith are disclosed and patented in my U.S. Patents No. 3,047,867 and No. 3,050,623.

Large numbers of the control elements may be assembled in panel-like arrays wherein an array of N^2 control elements may be controlled by $2N$ input functions. In display panel arrays such as this a plurality of longitudinally extending light conductor means 10 may be arranged in what is termed as X-control positions, and a combination of the first and second longitudinally extending electrodes may be duplicated and arranged in what is termed as Y-control positions. At each crossing of the light conductor means and the electrodes the photoconductive material will be allowed to function as a switch through which the phosphor associated therewith will be energized.

I have chosen to show a source of potential 11, an on-off switch 13, and variable resistors 15, 16 and 17 as a means of presenting a potential influence across the phosphor layers 5, 6 and 7 and the photoconductive material 9. It should, of course, be understood that similar control voltages may be derived from a number of other means that are well known to those skilled in the art. Light information being admitted to the light conductor means 10 may be derived from any one of numerous types of light wave generators, such as from cathode ray tubes, electroluminescent phosphor light generators, or the like.

Although I have limited myself to the showing of but one design configuration it should be understood by those skilled in the arts that the invention is not limited in this regard. For example, without departing from the invention, the three longitudinally extending electrodes 2, 3 and 4 may take the form of a single electrode, and the three individual layers of phosphor 5, 6 and 7 may be but a single layer designed to emit white light. Such a control element could be utilized in a greatly simplified array for merely black and white pictorial displays. It should also be understood that many of the other em-

bodiments embracing the general principles and constructions hereinbefore set forth, may be utilized and still be within the ambit of the present invention.

The particular embodiment of the invention illustrated and described herein is illustrative only, and the invention includes such other modifications and equivalents as may readily appear to those skilled in the arts, and within the scope of the appended claims.

I claim:

- 10 1. A crossed-grid electroluminescent phosphor illumination control element comprising:
  - (a) a plurality of longitudinally extending first electrodes;
  - (b) longitudinally extending light conductor means angularly displaced with respect to said longitudinally extending first electrodes, spaced apart therefrom and defining a crossing therebetween;
  - (c) photoconductive material presenting first and second light responsive portions, said first portion being intimately joined with said light conductor means coincident with said crossing and adapted to receive light from said light conductor means;
  - (d) electroluminescent phosphor intermediate said material and said first electrodes;
  - (e) a second electrode spaced apart from said phosphor and connected electrically with said material;
  - (f) means for presenting the influence of a combination of electrical potentials across said phosphor and said material intermediate said first electrodes and said second electrode; and means for deriving light radiation from said phosphor corresponding to said combination of electrical potentials upon the admission of light to said light conductor means;
  - (g) light control means intermediate the second portion of said material and said light conductor means for light insulating said second portion from said light conductor means; and
  - (h) means for exposing the second portion of said material to said light radiation from said phosphor.
- 20 2. A crossed-grid electroluminescent phosphor illumination control element comprising:
  - (a) a plurality of longitudinally extending first electrodes;
  - (b) longitudinally extending light conductor means angularly displaced with respect to said longitudinally extending first electrodes, spaced apart therefrom and defining a crossing therebetween;
  - (c) photoconductive material presenting first and second light responsive portions, said first portion being intimately joined with said light conductor means coincident with said crossing and adapted to receive light from said light conductor means;
  - (d) a plurality of layers of electroluminescent phosphor having different color emission characteristics intermediate, respectively, said plurality of first electrodes and said material;
  - (e) a second electrode spaced apart from said phosphor and operatively joined with said material;
  - (f) means for presenting the influence of a combination of electrical potentials across said phosphor and said material intermediate said first electrodes and said second electrode; and means for deriving from said phosphor a combination of colors corresponding to said combination of electrical potentials upon the admission of light to said light conductor means;
  - (g) light control means intermediate the second portion of said material and said light conductor means for light insulating said second portion from said light conductor means; and
  - (h) means for exposing the second portion of said material to said combination of colors from said phosphor.
- 30 3. A crossed-grid electroluminescent phosphor illumination control element comprising:
  - (a) a layer of photoconductive material presenting first and second light responsive portions;

- (b) a first light conductor means having a predetermined index of refraction for supporting said material and conducting light to the first portion of said material;
- (c) a second light conductor means having an index of refraction less than said predetermined index jacketing said first light conductor means for controlling the reflection of light through said first light conductor means and the reflection of light to the first portion of said material while preventing the exposure of the second portion of said material;
- (d) a plurality of layers of electroluminescent phosphor having different color emission characteristics adjacent said material;
- (e) means for presenting the influence of electrical potentials across said phosphor and said material; and
- (f) means for deriving light radiation from said phosphor upon the reflection of light from said second light conductor means to the first portion of said material.
4. An array of electroluminescent phosphor illumination control elements comprising:
- (a) a plurality of longitudinally extending first electrodes;
- (b) a plurality of longitudinally extending layers of electroluminescent phosphor joined, respectively, with said plurality of first electrodes;
- (c) a plurality of longitudinally extending light conductor means angularly displaced with respect to said longitudinally extending first electrodes, spaced apart therefrom and defining between them a plurality of crossings;
- (d) photoconductive material presenting first and second light responsive portions, intermediate said light conductor means and said phosphor coincident with said crossings and said first portion being adapted to receive light from said light conductor means and said second portion being adapted to receive light from said phosphor;
- (e) a second electrode spaced apart from said phosphor and connected electrically with said material.
5. An electroluminescent phosphor data display panel comprising:
- (a) a plurality of longitudinally extended light conductor means each having a predetermined index of refraction and light reflector means adapted to control the reflection of light waves through said light conductor means;
- (b) a plurality of longitudinally extended layers of electroluminescent phosphor angularly displaced with respect to said light conductor means and defining between them a plurality of crossings;
- (c) photoconductive material presenting first and second light responsive portions and said first portion being intimately joined with said light conductor means and said phosphor coincident with said crossings;
- (d) means for presenting the influence of electrical potentials across said phosphor and said material selectively and at predetermined crossings of said light conductor means and said phosphor;
- (e) means for presenting light selectively to said light conductor means; and
- (f) means for deriving light radiation from said phosphor at predetermined crossings of said light conductor means and said phosphor;
- (g) said light reflector means being adapted to light insulate the second portion of said material from said light conductor means; and
- (h) said second portion of said material being adapted to receive said light radiation.

6. An electroluminescent phosphor illumination control data display panel comprising:
- (a) a plurality of light conducting fibers each having a predetermined index of refraction and a light conducting jacket having an index of refraction less than said predetermined index;
- (b) a plurality of electrical conductors angularly displaced with respect to said fibers, spaced apart therefrom and defining between them a plurality of crossings;
- (c) photoconductive material presenting first and second light responsive portions, disposed upon said fibers coincident with said crossings;
- (d) said fibers being adapted to control the conduction of light to the first portion of said material and said jacket being adapted to light insulate the second portion of said material from said fibers and control the reflection of light through said fibers to the first portion of said material;
- (e) electroluminescent phosphor intermediate said photoconductive material and predetermined electrical conductors coincident with said crossings and intimately joined with said material and said conductors;
- (f) an electrode spaced apart from said phosphor and connected electrically with said photoconductive material;
- (g) said electroluminescent phosphor comprising a plurality of individual layers having different color emission characteristics;
- (h) means for presenting the influence of a combination of electrical potentials across said individual layers and said photoconductive material at predetermined crossings; and
- (i) means for deriving light radiation from said individual layers at a predetermined crossing and of a predetermined color upon the admission of light to predetermined light conducting fibers;
- (j) said second portion of said material being adapted to receive said light radiation from said layers.
7. A crossed-grid electroluminescent phosphor illumination control element comprising:
- (a) first and second longitudinally extending parallel electrodes supported in a spaced apart relationship;
- (b) at least one longitudinally extending light conductor means intermediate said first and second electrodes, angularly displaced with respect to said first and second electrodes and defining between them a crossing;
- (c) a layer of electroluminescent phosphor intimately joined with said first electrode coincident with said crossing;
- (d) photoconductive material presenting first and second light responsive portions intermediate said phosphor and said second electrode and connected electrically therewith, and the first portion of said material being intimately joined with said light conductor means coincident with said crossing;
- (e) light control means intermediate the second portion of said material and said light conductor means for light insulating said second portion from said light conductor means.
8. A crossed-grid electroluminescent phosphor illumination control element comprising:
- (a) first and second longitudinally extended parallel electrodes in different planes;
- (b) at least one longitudinally extended light conducting fiber intermediate said first and second electrodes defining a crossing between said fiber and said electrodes;
- (c) a layer of electroluminescent phosphor joined operatively with said first electrode coincident with said crossing;
- (d) photoconductive material presenting first and second light responsive portions intermediate said phosphor.

phor and said second electrode and connected electrically therewith;

- (e) said light conducting fiber optically connected to said material for the conduction of light to the first portion of said material coincident with said crossing; and
- (f) light reflector means intimately joined to said fiber for controlling the reflection of light through said fiber and to the first portion of said material while preventing the exposure of the second portion of said material.
